No. 844,799.

PATENTED FEB. 19, 1907.

C. J. HEISER.

TAP SOCKET.

APPLICATION FILED JULY 3, 1906.

UNITED STATES PATENT OFFICE.

CHARLES J. HEISER, OF EAST PITTSBURG, PENNSYLVANIA.

TAP-SOCKET.

No. 844,799.

Specification of Letters Patent.

Patented Feb. 19, 1907.

Application filed July 3, 1906. Serial No. 324,683.

To all whom it may concern:

Be it known that I, CHARLES J. HEISER, a citizen of the United States of America, residing at East Pittsburg, in the county of Allegheny and State of Pennsylvania, have invented certain new and useful Improvements in Tap-Sockets, of which the following is a specification, reference being had therein to the accompanying drawings.

10 This invention relates to tap-sockets particularly designed to be secured to or form a part of the spindle of a drilling-machine, lathe, or tapping-machine for the purpose of drilling and tapping holes or setting threaded studs or similar operations.

15 The object of this invention is to provide a flexible connection between the driving mechanism and the tap to permit the tap to stop or lag when for any reason the resistance is increased beyond a safe limit when a piece of material is being operated upon.

20 Another object of my invention is to provide an automatic device for controlling and protecting a tap, drill, bit, or similar instrument, said device being positive in its action, simple and inexpensive, and free from danger of injury by ordinary use.

25 With the above and other objects in view, which will more readily appear as the invention is better understood, the invention consists in the novel construction, combination, and arrangement of parts, to be presently described in detail and specifically pointed out in the appended claims.

30 In the drawings forming part of this specification, Figure 1 is an elevation of my improved tap-socket. Fig. 2 is a vertical sectional view of the same, partly in elevation. Fig. 3 is a cross-sectional view taken on the line *x-x* of Fig. 2. Fig. 4 is a similar view taken on the line *y-y* of Fig. 2. Fig. 5 is an enlarged perspective view of a driver-head, and Fig. 6 is an elevation of the driven tap-holder.

35 The socket consists of a sleeve 1, the one end of which is exteriorly threaded, as at 2, and interiorly threaded, as 3, while the opposite end of the sleeve is exteriorly threaded, as at 4. The sleeve is formed intermediate its ends with a horizontal partition 5, having a rectangular or oblong opening 6 formed therein, adapted to receive a rectangular block or lug 7, carried by a driver-head 8. The head normally rests upon the partition 5 and is temporarily held thereon by a coiled 40 spring 9, which is retained in the sleeve 1 by

adjustable means adapted to govern the tension of said spring.

Upon the top of the spring 9 is mounted a washer 10, engaged by a plurality of pins 11, 60 said pins extending through a shank-head 12, which is detachably held in the sleeve by the threads 3 thereof. The head 12 carries a conventional form of shank 14, adapted to be connected to and revolved by a drilling or 65 tapping machine. Mounted upon the upper ends of pins 11, which protrude above the head 12, is a washer 15, and engaging said washer is an interiorly-threaded thimble 16, having an exteriorly-knurled surface 17. By adjusting the thimble 16 the tension of the spring 9 can be increased or decreased, as occasion may necessitate.

In the opposite end of the sleeve 1 below the partition 5 is revolvably mounted a tap-holder 18, the upper end of which is provided with a diametrically-disposed groove 19, adapted to receive the block or lug 7 of the driver-head 8. The tap-holder 18 is retained in the sleeve 1 by a thimble 20, which is held 70 upon the sleeve 1 by the threads 4 thereof.

The block or lug 7 normally engages the tap-holder and causes it to revolve; but to permit of the driver-head easily receding when the resistance of the tap-holder is increased beyond a safe limit I bevel the side edges of the lug 7 and the groove 19.

75 In operation, the tension of the spring 9 maintains a frictional contact between the driver-head 8 and the tap-holder 18, the degree of friction being of sufficient strength to drive the latter when said tap-holder is meeting with its ordinary or safe cutting resistance; but should the resistance become excessive, which would tend to strain or break the tap- 80 socket, the tension of the spring 9 will be overcome and the block or lug 7 will slip and recede, permitting the tap-holder to remain stationary while the shank 14 and its appurtenant parts would continue to revolve.

85 To facilitate the tension adjustment of the spring 9, the thimble 16 can be graduated, also the sleeve 1 contiguous to the thimble, whereby the amount of movement on the part of the washer 10 can be expeditiously 90 determined.

95 The driver-head 8, tap-holder 18, pins 11, and washers 10 and 15 are made of metal having tenacious and durable properties.

100 What I claim, and desire to secure by Letters Patent, is—

1. In a tap-socket, the combination with a

revoluble shank having a threaded head, and a tap-holder having a grooved end, of a partitioned sleeve carried by the head of said shank and surrounding the grooved end of said holder, a driver-head engaging the partition in said sleeve and having a lug projecting through the said partition and engaging in the groove of said holder, yielding means to normally hold said lug in said groove, and means to adjust the last-named means, said adjusting means embodying a plurality of pins loosely mounted in the head of said shank and engaging the first-mentioned means, and a thimble adjustably mounted upon said sleeve and engaging said pins, substantially as described.

2. In a tap-socket, the combination of a tap-holder, a driver-shank having a head, a sleeve connecting the head of the driver-shank with the tap-holder, a partition in said sleeve

having an opening therethrough, a driver-head seated on said partition and having a lug projecting therethrough and engaging in a recess provided therefor in the end of the tap-holder, a spring interposed between the driver-shank head and the driver-head for normally holding the lug of the latter seated in the recess in the tap-holder, a washer resting on said spring, pins loosely mounted in the driver-shank head and engaging said washer and a thimble on the sleeve and engaging said pins for regulating the tension of said spring.

In testimony whereof I affix my signature in the presence of two witnesses.

CHARLES J. HEISER.
